UNITED STATES PATENT OFFICE.

AMOS E. WHIPPLE, OF WHITINSVILLE, MASSACHUSETTS, ASSIGNOR TO WHITIN MACHINE WORKS, OF WHITINSVILLE, MASSACHUSETTS, A CORPORATION OF MASSACHUSETTS.

THREAD GUIDE.

Application filed March 19, 1923. Serial No. 626,010.

To all whom it may concern:

Be it known that I, AMOS E. WHIPPLE, United States citizen, residing in Whitinsville, Massachusetts, have invented the following described Improvements in Thread Guides.

The invention relates to thread guides for wet twisters and like machines, and its object is to provide an improved holder for the 10 non-corrodible or ceramic guide eyes, used in such machinery, which adequately protects the guide eye from injury as by contact with bobbins and which is least likely to catch or snarl the yarn and which is capable of being made at small expense from sheet metal, and which may also be used on various standard types of finger heads or thread board rails.

In the accompanying drawing Fig. 1 represents a partial perspective view of a 20 thread board rail with finger heads having one form of the invention applied to them. Fig. 2 is an enlarged perspective of this form, Fig. 3, a top plan thereof, Fig. 4 a 25 longitudinal section of Fig. 3 on line IV—IV. Fig. 5 is a top plan of another and preferred form of the invention, Fig. 6 a bottom plan thereof, Figs. 7 and 8, sections on line VII—VII and VIII—VIII respectively of Fig. 5, and Fig. 9, a longitudinal section of Fig. 5.

The guide eye is formed with the usual 30 yarn hole through which the yarn passes and by which it is guided, and also with an oblique entrance slot through which the yarn may be laterally introduced into such hole. This entrance slot may be variously formed but in the case taken for illustration, it is formed by the space between two opposing 40 overlapping and relatively slender horns 1, which makes an efficient form of guide eye. It will be understood that when the yarn has been laterally entered into the hole, through the oblique slot between the horns, it is 45 then very surely confined in the hole against accidental escape. Such guide eyes are commonly made of highly glazed ceramic or other vitreous material like porcelain, and in the process of doffing and replacing bobbins, they are apt to be struck from below 50 as well as from above and, as heretofore mounted, they are very frequently broken, or dislodged by such contact. According to the preferred form of this invention, such a

ceramic guide eye is shaped so that its 55 smaller cross-sectional dimension is at its rear end, for example, it is tapered toward the rear and it is also formed with a retaining recess or lock hole, such as indicated at 2, toward its rear end, this recess or hole 60 being adapted to cooperate with a complementary retaining means or lock pin in the holder, as later described.

The holder is constituted at its forward 65 end as a box which conforms in a general way to the tapered shape of the guide eye and surrounds and protects it on its bottom as well as on its top and sides, but so as to leave the yarn hole and entrance slot exposed and accessible for the introduction and passage of the yarn. That is to say, the box end of the holder is provided with an end-wise recess 3 in its top wall and with a corresponding recess 4 in its bottom wall, 70 both deep and wide enough to expose the 75 oblique entrance slot and yarn hole. Said recesses are desirably shaped or cut as to form projections such as 3^a and 4^a, in each recess as shown in Figs. 5 and 6, respectively. Such projections overlie and specially protect the two horns and they may obviously be extended further over the horns than shown in the drawings, to provide greater protection than indicated. The walls of the 80 eye box at its rear or smaller end are integrally extended as a shank which may be 85 either flat, channeled, round or other shape, as desired, so as to be adapted to be received in, and adjustably supported by, a finger head. In Figs. 1 to 4 this rearward 90 extension 6 is substantially flat or channel-shaped and also slotted for adjustable attachment to the finger head 5 by the usual bolt, as indicated in Fig. 1. In Figs. 5 to 9 the integral extension 7 of the guide box is 95 round or cylindrical and adapted to be adjustably held in the cross bore of a rotary barrel 8 by a longitudinal set screw 9. The barrel 8 is mounted to rotate in a slotted 100 knuckle 10 mounted on the thread board rail according to familiar design. The round shank 7 enables the guide to be set in or out of the barrel and also turned axially, as will be understood.

The box-form guide holder, in both forms 105 of the invention, is preferably made from a sheet metal blank of which the forward end is first slotted to form the recesses and

- horn-protecting projections above referred to and then folded to form the top, bottom and side walls of the box. In Figs. 2 to 4 the rearwardly extended top and side walls 5 of the box part form a channelled shank. In Figs. 5 to 9 the rearwardly extended top and side walls are rolled or folded to form a round or cylindrical shank and in order to guard against subsequent deformation, by 10 the pressure of the set screw 9, the sheet metal may be rolled around a section of round rod 11 serving as a reinforcing core therefor.
- The guide eye may be fastened in the box 15 by various means, but it is deemed best to pin it therein, for which purpose the top and bottom of the box walls are one or both perforated in registry with the perforation 2 in the rear smaller end of the guide eye.
- 20 When the supporting box is folded of sheet metal, which as stated is preferred, it is expandible and the insertion therein of the guide eye slightly spreads the walls so that when the retaining pin 12 has been engaged in hole 2, it holds the eye in a position where 25 it is subject to the elastic pressure of the side walls, thus guarding against rattling by vibration. The pin 12, in the case in hand, preferably extends entirely through the box, 30 terminating flush with the lower wall or projecting slightly beyond it, in which case it is rounded or it may be upset. In any case it can be removed so that the guide eyes when worn may be replaced. It will be apparent 35 that the specific form of the retaining-means is very obviously capable of considerable variation; its essential function of course is to hold the eye against escape from the box, and for this purpose it may be designed in several ways. The pin 12 is 40 satisfactory because it is substantially flush with the box wall and leaves no opening likely to collect dirt. As a matter of appearance the meeting edges of the folded 45 box walls are located at the bottom of the box and the rear end of the box part is tapered and smoothly merged into the round extension shank 7, so that the whole of the exterior surface of the device is thus smooth 50 and devoid of abrupt shoulders or projections likely to catch on the yarn. It is thus also more easily kept clean.
- Claims:
1. Thread guide construction for wet 55 twisters, etc., comprising a ceramic guide eye, a supporting box therefor formed of sheet metal protecting said eye on its top, sides and bottom, said box being externally smooth and having an integral sheet metal 60 extension forming a shank and a finger head provided with means for adjustably receiving and supporting said shank.
  2. Thread guide construction for wet 65 twisters, etc., comprising a ceramic guide eye having a yarn hole and an oblique en-
- trance slot, a supporting box therefor recessed top and bottom to expose said hole and slot but elsewhere protecting said eye, and an integral extension of said box forming a shank to be received in a finger head. 70
3. Thread guide construction for wet twisters, etc., comprising a ceramic guide eye having an oblique yarn entrance slot formed by overlapping horns, a supporting box therefor recessed top and bottom to 75 form projections protecting said horns and an integral shank extension of said box adapted to be received in a finger head.
4. Thread guide construction for wet 80 twisters, etc., comprising a ceramic guide eye having a retaining means or recess, a metal supporting box for said eye having a retaining member engaging said retaining means on the eye and an extension on the box adapted to be supported in a finger head. 85
5. Thread guide construction for wet 90 twisters comprising a ceramic guide eye having its least cross-sectional dimension at its rear end, a supporting box therefor shaped to receive said eye, a retaining means for the eye and an integral extension from the smaller end of said box adapted to be received in a finger head.
6. Thread guide construction for wet 95 twisters, etc., comprising a ceramic guide eye perforated to receive a retaining pin, a perforated sheet metal supporting box for said eye, a retaining pin occupying the perforations in said box and eye and an integral extension on the box adapted to be 100 supported in a finger head.
7. Thread guide construction for wet 105 twisters, etc., comprising a metal supporting box formed with elastically yielding walls, a guide eye adapted to spread said walls when inserted in the box and means for retaining the eye in such wall-spreading position.
8. Thread guide construction for wet 110 twisters, etc., comprising a guide eye and a holder therefor comprising a sheet metal blank folded at its front end to form a box covering and protecting said eye on its bottom and top, the rear of said blank being longitudinally bent or folded to form a shank adapted to be adjustably received in 115 a finger head.
9. Thread guide construction for wet 120 twisters, etc., comprising a guide eye and a holder therefor comprising a sheet metal blank folded at its front end to form a box protecting the bottom of said eye and at its rear end to form a round shank adapted to be adjustably received in a finger head.
10. Thread guide construction for wet 125 twisters, etc., comprising a guide eye and a sheet metal holder therefor having its rear end rolled around a core and forming a supporting shank for said eye.
11. Thread guide construction for wet 130 twisters, etc., comprising a guide eye, a sup-

porting box therefor formed of a folded sheet metal blank having yielding walls, a guide eye adapted to spread said walls by insertion in the box, means for retaining the 5 eye in its inserted position, and an integral rearward extension of said box folded to form a supporting shank for said guide eye.

12. Thread guide construction for wet 10 twisters, etc., comprising a ceramic guide eye, a supporting box therefor formed of a folded sheet metal blank surrounding and protecting said eye on its bottom, said box being externally smooth and tapered rear- 15 wardly into an integral round sheet metal shank extension adapted to be supported in a finger head.

13. Thread guide construction comprising 20 a tapered guide eye and a holder therefor formed of a sheet metal blank folded to form a tapered box at its front end and folded at its rear end to form a supporting shank for said eye.

14. Thread guide construction for wet 25 twisters, etc., comprising a ceramic guide eye having its least cross-sectional dimen-

sion at its rear end and perforated at such end, a tapered supporting box therefor, having a retaining pin for the perforation and an integral extension from the smaller end 30 of said box adapted to be received in a finger head.

15. A guide embodying a member having a longitudinally extended recess to receive 35 an eye and a notch extended at right angles to the length of said recess and communicating therewith.

16. A guide comprising a member having between the side walls thereof an open- 40 ended recess to receive removably an eye, and a notch extended entirely through said side walls and intersecting said recess.

17. A guide comprising a member having between the side walls thereof an open- 45 ended recess and a notch extended entirely through said side walls and intersecting said recess, and an eye removably mounted in said recess and having a slit located to register with said notch.

In testimony whereof, I have signed this 50 specification.

AMOS E. WHIPPLE.
